UNITED STATES PATENT OFFICE.

WALTER DE VILLE, OF EAST LIVERPOOL, OHIO, ASSIGNOR TO THE PALM BROTHERS COMPANY, OF NEW YORK, N. Y.

DESIGN FOR AN ARTICLE OF MANUFACTURE.

47,377.

Specification for Design.

Patented May 25, 1915.

Application filed February 5, 1915. Serial No. 6,387. Term of patent 7 years.

To all whom it may concern:

Be it known that I, WALTER DE VILLE, a citizen of the United States, residing at East Liverpool, in the county of Columbiana and State of Ohio, have invented a new, original, and ornamental Design for an Article of Manufacture, of which the following is a specification, reference being had to the accompanying drawing, forming part thereof.

The figure is a plan view of my design to be applied to an article of manufacture. I claim:

The ornamental design for an article of manufacture as shown.

WALTER DE VILLE.

Witnesses:

ALLEN H. JACKMAN,
JOSEPH S. KEDDIE.
